Inventor:

Francis Frye.

UNITED STATES PATENT OFFICE.

FRANCIS FRYE, OF TIME, ILLINOIS.

IMPROVEMENT IN WINNOWING-MACHINES.

Specification forming part of Letters Patent No. 58,630, dated October 9, 1866.

To all whom it may concern:

Be it known that I, FRANCIS FRYE, of Time, in the county of Pike and State of Illinois, have invented a new and Improved Winnower; and I do hereby declare that the following is a full, clear, and exact description thereof, reference being had to the accompanying drawings, forming part of this specification.

The nature of my invention consists in so combining an eccentric to an upright lever which is connected to a screen or fan for cleaning grain as to produce a regular longitudinal reciprocating motion to the screen of a winnowing machine.

To enable others skilled in the art to make and use my invention, I will proceed to describe its construction and operation.

Figure 1 is a side elevation of my improved fan. Fig. 2 is a longitudinal vertical sectional elevation of the same. Fig. 3 is also a side elevation of the same opposite from Fig. 1.

Letters of like name and kind refer to like parts in each of the figures.

A represents the frame of my improved fan, made of wood, of suitable dimensions, which supports the machinery of the fan. B is the hopper, which is also made of wood, and located upon the top of the frame A and immediately over the screen or riddle C. D is a lever attached by a pivot at the lower end to the frame, and extends up, and at the top is a cross-beam attached, upon which rests the screen C. In this lever D is a slot, a, in which is fitted and

works an eccentric, E, which is made fast to the fan-shaft F, and to which are connected the fans G, that run in the fan-case H. I is a spur-gear wheel, that is secured to a shaft that runs in proper bearings J, that are secured to the frame A. This gear-wheel I is provided with teeth that mesh into a corresponding pinion, K, that is secured to the fan-shaft F.

L is a deflecting-board, that conducts the grain as it falls through the screen to the opening at O, where the grain enters the air channel or throat, when it receives the action of the blast and falls down and is discharged at the arrow P, and the chaff is blown out by the blast through the opening Q, and the chaff out at S.

R is a door located at the side of the fan-case for the purpose of admitting air to the fan-case. T is the crank by which the fan is operated.

Having thus described my invention, what I claim as new, and desire to secure by Letters Patent, is—

1. The eccentric E and lever D, in combination with the hopper B and screen C, substantially as and for the purposes set forth.
2. The lever D and eccentric B, in combination with the fans G, for the purposes and substantially as herein shown and described.

FRANCIS FRYE.
